Primary Examiner — Mark A Goodwin(74) *Attorney, Agent, or Firm* — Christopher J. Owens(57) **CLAIM**

We claim the ornamental design for a stump cutter tooth, as shown and described.

DESCRIPTION

FIG. 1 is a front isometric view of a stump cutter tooth showing our new design;

FIG. 2 is a rear isometric view of the stump cutter tooth of FIG. 1;

FIG. 3 is a rear view of the stump cutter tooth of FIG. 1; FIG. 4 is a front view of the stump cutter tooth of FIG. 1; FIG. 5 is a left-side view of the stump cutter tooth of FIG. 1;

FIG. 6 is a right-side view of the stump cutter tooth of FIG. 1;

FIG. 7 is a bottom view of the stump cutter tooth of FIG. 1; and,

FIG. 8 is a top view of the stump cutter tooth of FIG. 1. The broken line showing in FIGS. 1-8 is included for the purpose of illustrating portions of the stump cutter tooth and forms no part of the claimed design.
